(57) **CLAIM**

The ornamental design for a ruler with rounded ends, as shown and described.

DESCRIPTION

FIG. 1 is a top plan view of a ruler with rounded ends showing our new design;

FIG. 2 is a front elevational view thereof, the rear elevational view thereof being identical;

FIG. 3 is an enlarged left side view thereof, the right side view thereof being identical;

FIG. 4 is an enlarged central cross-sectional view thereof showing the contours in more detail;

FIG. 5 is a top plan view of a second embodiment of a ruler with rounded ends showing our new design;

FIG. 6 is a front elevational view thereof of the ruler with rounded ends of FIG. 5, the rear elevational view thereof being identical; and,

FIG. 7 is a left end view of the ruler with rounded ends of FIG. 5, the right end view thereof being identical.

No claim is made to the specific measurement scales for the embodiment of FIGS. 5-7.
